[57] CLAIM

The ornamental design for an aerosol dispenser, as
shown and described.

DESCRIPTION

FIG. 1 is a front elevational view of an aerosol dis-
penser showing our new design;

FIG. 2 is a side elevational view thereof, the undis-
closed opposite side being a mirror image;

FIG. 3 is a rear elevational view thereof;

FIG. 4 is a top plan view thereof;

FIG. 5 is a bottom plan view thereof;

FIG. 6 is a front elevational view of a second embodi-
ment of an aerosol dispenser disclosed in FIG. 1;

FIG. 7 is a side elevational view of FIG. 6, the undis-
closed opposite side being a mirror image;

FIG. 8 is a rear elevational view of FIG. 6; and,

FIG. 9 is a top, front and right side perspective view of
FIG. 1.
